UNITED STATES PATENT OFFICE.

HENRY F. MUELLER, OF NEW ORLEANS, LOUISIANA.

DESIGN FOR A COTTON-TIE BUCKLE.

SPECIFICATION forming part of Design No. 25,861, dated August 4, 1896.

Application filed June 27, 1896. Serial No. 597,259. Term of patent 14 years.

To all whom it may concern:

Be it known that I, HENRY F. MUELLER, a citizen of the United States, residing at New Orleans, in the parish of Orleans and State of 5 Louisiana, have invented a new and original Design for Cotton-Tie Buckles, of which the following is a specification.

This invention relates to a new and original design for cotton-tie buckles, and it has 10 for its object to provide a design of this character that shall be both useful and ornamental.

The leading feature of the design resides in 15 a rectangularly-shaped body having a rectangular opening therein and opposite L-shaped arms merging into the rectangular body at the diametrically opposite corners of one end of the body, said L-shaped arms having rounded outer ends and having their longer 20 portions disposed in the same direction and lying parallel with the adjacent sides of the rectangularly-shaped body.

In the drawings, Figure 1 is a perspective 25 view of the cotton-tie buckle embodying the herein-described design. Fig. 2 is a plan view thereof.

Referring to the drawings, the numeral 1 designates a rectangularly-shaped body comprising opposite parallel side and end portions 2 and 3, respectively, said side and end 30 portions of the body forming the boundary lines of a central rectangular opening 4. The body 1 is provided with diametrically opposite rounded corners 5 at one end, and merging into the diametrically opposite corners at the 35 other end of the body is a pair of L-shaped arms 6. The arms 6 are provided with outer rounded ends 7, and the longer portions of said arms are disposed in the same direction with respect to the body and lie parallel with 40 the adjacent sides of the body.

What I claim is—

The design for a cotton-tie buckle herein shown and described.

In testimony that I claim the foregoing as 45 my own I have hereto affixed my signature in the presence of two witnesses.

HENRY F. MUELLER.
